(57) **CLAIM**

The ornamental design for a power supply case for welding, cutting, or heating power, as shown and described.

DESCRIPTION

FIG. 1 is a top perspective view of a power supply case for welding, cutting, or heating power showing our new design; FIG. 2 is a front elevation view thereof; FIG. 3 is a rear elevation view thereof; FIG. 4 is a right-side elevation view thereof; FIG. 5 is a left-side elevation view thereof; FIG. 6 is a top plan view thereof; and, FIG. 7 is a bottom plan view thereof. The dashed broken lines in the figures depict portions of the power supply cases that form no part of the claimed designs.
